Primary Examiner — David Muller

(74) Attorney, Agent, or Firm — John P. McGonagle

(57) **CLAIM**

The ornamental design for a medical bracket and clamp, as shown and described.

DESCRIPTION

FIG. 1 is a top perspective view of a medical bracket and clamp showing my new design.

FIG. 2 is a side view thereof, the opposite side being a mirror image thereof;

FIG. 3 is a rear view thereof;

FIG. 4 is a top view thereof;

FIG. 5 is a bottom view thereof; and,

FIG. 6 is a front view thereof.

The partial view of a hospital bed end and cables shown in broken lines depict environmental structure only and form no part of the claimed design.

1 Claim, 3 Drawing Sheets
